(57) **CLAIM**

The ornamental design for a mirrored dispensing cap for a lotion container, as shown and described.

DESCRIPTION

FIG. 1 is an upper right/front perspective view of a first embodiment of a mirrored dispensing cap for a lotion container, with the cap shown in a fully closed state;

FIG. 2 is front-side view thereof;
FIG. 3 is back-side view thereof;
FIG. 4 is left-side view thereof;
FIG. 5 is right-side view thereof;
FIG. 6 is a top view thereof;
FIG. 7 is a bottom view thereof;
FIG. 8 is an upper front/right perspective view thereof, with a top cap segment shown in an opened state and with a bottom cap segment shown in a closed state;
FIG. 9 is an upper back/left perspective view thereof, with a bottom cap segment shown in an opened state and with a top cap segment shown in a closed state;
FIG. 10 is an upper front/right perspective view thereof, with both a top cap segment and a bottom cap segment shown in an opened state;
FIG. 11 is a left-side view thereof, with both the top cap segment and the bottom cap segment shown in an opened state, the right-side view, not shown, being a mirror-image of the left-side view;
FIG. 12 is a front-side view thereof, with the cap shown in a fully closed state and depicted on top of a lotion container;
FIG. 13 is a left-side view thereof, with the cap shown in a fully closed state and depicted on top of a lotion container, the right-side view, not shown, being a mirror-image of the left-side view;
FIG. 14 is an upper front/right perspective view thereof, with the cap shown in a fully closed state and depicted on top of a lotion container;
FIG. 15 is front-side view of a second embodiment of a mirrored dispensing cap for a lotion container that is the same in all respects to the first embodiment, but depicts a middle cap having a shorter height;
FIG. 16 is a back-side view thereof;
FIG. 17 is left-side view thereof; and,
FIG. 18 is right-side view thereof.
The broken lines in the drawings depict environment only, and form no part of the claimed design.
The top surface of the middle segment shown in FIGS. 8 and 10 includes a mirrored surface that extends entirely within the raised circular ridge.
